UNITED STATES PATENT OFFICE

2,427,234

VERTICALLY ADJUSTABLE SEAT

Nathaniel T. Shepherd, Salt Lake City, Utah

Application April 23, 1942, Serial No. 440,145

1 Claim. (Cl. 155—88)

1

The invention relates generally to posture chairs and more particularly to improvements in vertically adjustable seats.

The so-called posture chairs used extensively in clerical offices, schools, etc., are characterized by the adjustability of the seat for depth and height and of the back rest for height and angle. Heretofore such chairs have been commonly made entirely of metal except for the seat cushions. Having in view the current severe restrictions on the use of metals in articles of the class under consideration, one object of the present invention is to provide a chair of substantially all wood construction which has the usual features of adjustment of the metal posture chairs but in which the use of metal is reduced to a negligible amount.

Another object is to provide novel seat adjusting means particularly suitable for chairs of wood construction whereby the seat may be quickly and accurately adjusted for height and for depth.

Another object is to provide a cushioned seat chair of novel and improved construction adapted for the use of removable seat covers and in which the seat portion may be readily detached for replacement of the cushion or cover.

Another object is to provide an improved height adjusting mechanism particularly suitable for chairs of wood construction which mechanism is efficient and reliable in action yet extremely simple and inexpensive to manufacture and which requires relatively little metal in its construction.

Other objects and advantages of the invention will become apparent from the following detailed description of the preferred embodiments illustrated in the accompanying drawings in which:

Figure 1 is a front elevational view of a chair having a vertically adjustable seat embodying the features of the invention.

Fig. 2 is a fragmentary vertical sectional view of the chair taken substantially along the line 2—2 of Fig. 1.

Fig. 3 is a horizontal sectional view of the chair taken substantially along the line 3—3 of Fig. 2.

Fig. 3a is a fragmentary bottom view of the seat assembly.

Fig. 4 is a vertical sectional view of the chair seat and base taken along the line 4—4 of Fig. 3.

Fig. 5 is a fragmentary vertical sectional view of the chair base taken along the line 5—5 of Fig. 3.

2

Fig. 6 is a horizontal sectional view of the back rest taken along the line 6—6 of Fig. 1.

Fig. 7 is a vertical sectional view of a modified form of the chair equipped with a combined swiveling and height adjusting mechanism.

Fig. 8 is a vertical sectional view of the modified form of chair taken along the line 8—8 of Fig. 7.

Fig. 9 is a horizontal sectional view of the 10 modified chair taken along the line 9—9 of Fig. 7.

Fig. 10 is a horizontal sectional view similar to Fig. 9 but showing another modified form of the chair.

Fig. 11 is a fragmentary vertical sectional view 15 of the modified form of chair taken along the line 11—11 of Fig. 10.

Fig. 12 is a fragmentary vertical sectional view of the chair taken along the line 12—12 of Fig. 10.

While the invention in its broader aspects is 20 adapted for use in various types of chairs, certain of the important features are especially suited for use in so-called posture chairs. The invention has therefore been disclosed as embodied in a chair of this character for purposes of illustration. It is to be understood, however, that various changes, modifications and adaptations may be made in the form, construction and arrangement of the parts without departing from the spirit and scope of the invention as 25 expressed in the appended claim.

Referring now to Fig. 1 of the drawings, the preferred form of chair selected to illustrate the invention comprises generally a base 15 adapted to be supported on the floor, a seat assembly 16 30 adjustably mounted on the base, and a back rest 17 adjustably carried on an upright back frame extending upwardly from the base. The framework of the chair is constructed substantially entirely of wood or like material except for the 35 cushions and covers and the fittings, such as bolts and screws, for connecting the various parts subject to the greatest strains. Moreover, the parts have been constructed and arranged to use only the simplest types of fittings and only those essential for the proper functioning of the chair 40 structure. In this way, the metal requirements of the improved chair have been reduced to a negligible amount.

As will be seen by reference to Figs. 1, 2 and 3, 45 the base 15 comprises a generally rectangular box-like section formed by a bottom plate 20 to which four supporting legs 21 are rigidly secured as by screws 22. The legs are equipped with conventional casters 23. Preferably, the legs are 50 bowed outwardly to provide a greater spread at

their point of contact with the floor and thus increase the stability of the chair.

Rigid with the bottom plate 20 are a pair of upstanding side members or panels 25 spaced apart on opposite sides of the bottom plate and arranged in substantially parallel relation. A back panel 26 and a front panel 27 close the front and rear ends of the box-like section of the base. The back panel 26 is rigidly secured in place while the front member 27 is removably mounted for reasons to appear presently.

The seat assembly, as herein shown, comprises a flat cushion supporting member 28 of generally oval contour as shown in Fig. 3a. A cushion or pad 29 of resilient material is positioned on the top of the member 28 and is enclosed and held in place thereon by a cover 30 of any suitable material adapted to have its marginal edge portion turned under the supporting member. The said edge portion of the cover may be formed with a hem or casing 31 through which a gather-cord 32 may be drawn to stretch the cover tightly over the cushion and to hold it securely in place.

The seat assembly is adapted to be supported on the base for adjustment vertically, that is, for height, and from front to rear, or for depth, by supporting and guiding means of novel construction. The supporting and guiding means preferably comprises coacting elements in the form of parallel guide elements or tongues 33 rigid with but spaced downwardly from the seat member 28 and adapted to slidably engage in grooves 34 formed in the inner faces of the side panels 25, as best shown in Fig. 4. As herein shown, the tongues 33 are formed on the lower outer edges of a pair of supporting members 35 rigidly attached to the underside of the cushion supporting member 28 in laterally spaced relation. The members 35 are substantially shorter than the cushion supporting member 28 and are set inwardly from the front and side edges thereof so as to leave a part of the marginal edge portion of the member unobstructed for the reception of the seat cover. The members, however, extend substantially to the rear edge of the supporting member and suitable notches or slots 36 are provided therein for the reception of the seat covers. These slots are preferably dimensioned to receive the edge of the seat cover with a tight frictional fit and are thus effective to hold the cover against displacement with respect to the cushion 29.

As will be seen by reference to Figs. 3 and 4, the members 35 are spaced apart so as to fit snugly between the side panels 25 with the tongues 33 entered in the grooves 34. To provide for vertical adjustment of the seat assembly, a series of such grooves are formed in each panel 25, the grooves being spaced apart vertically of the panel and arranged to present opposed pairs on opposite sides of the base. A reinforcing member 38 connected between the lower edges of the members 35 serves to hold the members rigidly in predetermined position with the tongues 33 properly spaced for coaction with the grooves 34.

With the supporting and guiding means above described, the height of the seat cushion may be adjusted as required by engaging the tongues 33 in any selected pair of the grooves 34. When it is desired to transfer the seat assembly from one pair of supporting grooves to another, it is necessary first to remove the front panel 27 of the base so that the tongues may be withdrawn from the grooves in which they are currently entered. To permit such removal, the front panel is formed with tongues 41 at each end engageable in ver-

tically disposed slots 42 in inner faces of the side panels 25. These slots are terminated substantially above the bottom edge of the side panels and the tongues 41 are similarly dimensioned so that the panel is supported thereby independently of the bottom member 20. When the panel is in place, it serves to confine the seat assembly within the box-like base. In other words, the front panel performs the dual function of limiting the forward movement of the seat assembly and enclosing the front of the base to give it a neat and attractive appearance.

While the seat assembly is confined within predetermined limits by the front panel of the base 15 and the back frame of the chair, a substantial range of movement is permitted by reason of the fact that the supporting members 35 are substantially shorter than the grooved side panels 25 with which they coact. Thus a substantial range of adjustment for depth, that is, adjustment of the seat assembly from front to rear, is permitted. The seat assembly may be locked in any adjusted position by means of a set screw 43 or the like threading into one of the side panels and engaging the companion supporting member of the seat assembly. Ordinarily it will be found desirable to dispense with the use of the locking screw since the frictional resistance of the interengaging tongues and grooves is sufficient to prevent sliding of the seat when the chair is occupied. However, instant adjustment of the seat may be effected by simply relieving the seat of the weight of the user and shifting it either forwardly or rearwardly as desired. This can be done very conveniently by gripping the edges of the seat in the hands while partially rising from the sitting position.

Rigid with the base 15 is the back frame of the chair on which the back rest 17 is carried. The back frame, as herein shown, comprises a pair of upright members 45 and 46 rigidly anchored to the base in any suitable manner, preferably at the rear corners thereof as shown in Fig. 3. In the particular chair illustrated, the side panels 25 and the rear panel 26 of the base are mortised into the adjacent sides of the members 45 and 46 to provide a strong and rigid frame structure. A cross bar 47 connected between the upright members intermediate their ends serves to reinforce the back frame and to hold the members in fixed spaced relation.

The back rest 17 in its preferred form, as shown in Figs. 1, 2 and 6, is of simple yet rugged construction. In the form illustrated, the back rest 55 comprises a back plate 50 of wood or like material of generally oval contour bent to present a concave front surface and convex rear surface as shown in Fig. 6. A cushion or pad 51 of suitable resilient material is mounted on the front or convex face of the member and is held thereon by a removable cover 52. This cover is preferably of the type having a marginal edge portion adapted to fit over the edges of the back member and is desirably formed with a hem or casing 53 through which a draw-cord 54 may be threaded to hold the cover in place.

The back member 50 is suitably secured as by bolts 55 to a cross member or swivel bar 56 adapted to be pivotally supported between the upright members of the back frame. The swivel bar is preferably formed with an arcuate or concave recess 57 dimensioned to receive the convex face of the back member 50 and to provide a relatively long bearing surface effective to prevent warping of the member or other change from its arcuate

form. With this arrangement the edge portions of the back member extend clear of the associated parts of the back rest and back frame and thus provide convenient access for the installation or replacement of the cover.

To provide for adjusting the back rest to accommodate persons of different height, the swivel bar 56 is adapted to be detachably secured between the upright members 45 and 46 in any selected one of a plurality of vertically spaced positions. To this end the upright members are formed with a series of vertically spaced recesses 58 and the swivel bar 56 is provided at each end with projecting pins 59 and 60 of wood, metal or other suitable material adapted to engage in said recesses. The pin 59 is preferably fixed while pin 60 is constructed in the form of a plunger adapted for retraction axially to withdraw it from the recess whereby the entire back rest assembly may be tilted to withdraw the companion pin from its recess. To this end the pin 60 is slidably supported in a suitable bore 61 and a spring 62 inserted in the bore acts against the inner end of the pin to urge the same outwardly. An arm 63, threaded into or otherwise suitably secured to the pin and projecting laterally therefrom through a slot 64 in the swivel bar 56 serves to limit the outward movement of the pin and provides a convenient manually operable means by which the pin may be retracted from the recess in which it is fitted.

The mounting of the back rest on the frame by means of the pins 59 and 60, as above described, in addition to permitting convenient adjustment of the back rest for height also permits the swiveling of the rest about a horizontal axis. Thus the rest is readily shiftable to the desired angle by pressure of the back of the person sitting in the chair. The weight of the cushion tends to rock the back rest into a horizontal position but such movement is limited by the cross bar 47 which acts as a stop for the rest. For this purpose, the bar is adapted to coact with the lower edge of the back rest in any of its adjusted positions to hold the same in a substantially vertical position as shown in Fig. 2. The cross bar may be notched as at 65 for the reception of the back of the member 50, the depth of the notch determining the normal position of the member and the cushion with which it is equipped.

The modified form of chair shown in Figs. 7, 8 and 9 embodies all the features of adjustment of the chair structure previously described and in addition provides a swiveling action for the seat which is advantageous under some conditions of use. In general, this chair utilizes the same back rest 17 and the same seat assembly 16. In this instance, however, the base is simply a flat, generally rectangular top member 70 of wood or other suitable material to which the legs 21 are attached.

Adjustable support for the seat assembly is provided by a seat frame 71 supported on the base to rotate or swivel about a vertical axis. The seat frame 71, as shown in Figs. 7-9, comprises a bottom plate 72 with upstanding side panels 73 at each side edge. A back panel 14 and a front panel 75 are assembled therewith to form an open topped box-like structure of generally rectangular form. Side members 45 and 46 of the back frame are mortised or otherwise rigidly joined to the side and back panels of the seat frame at the rear corners thereof, as shown in Fig. 6.

The side panels 73 are similar in general to the panels 25, previously described, in that they

are provided with one or more sets of horizontally disposed grooves 76 for slidably receiving the tongues 33 of the seat assembly 16, which, as stated above, may be identical with that previously described. A single groove 76 is shown in Figs. 7 and 8 by way of illustration, thus providing depth adjustment of the seat while adjustment for height is obtained through the swivel mechanism, as will appear presently. It will be understood, of course, that a plurality of the grooves 76 may be provided similar to the grooves 34, thus giving wider range of adjustment for height than is obtained by the swiveling mechanism alone.

15 Regardless of the number of grooves 76 provided in the seat frame panels, the front panel 75 is assembled therewith so that it may be removed to permit withdrawal of the seat assembly for replacement of the cover or other purposes. To this end, the panel 75 is formed with tongues 77 at each end adapted to slidably engage in vertically disposed slots 78 in the side panels 73 as shown in Fig. 9. The tongues and notches are terminated substantially above the lower edges of the 20 respective members, as shown in Fig. 7, so that the weight of the panel member is carried on the tongues. With this arrangement the panel member may be extended over the front edge of the bottom plate 72 to conceal the same and thus enhance the appearance of the chair structure.

25 The mechanism which provides the swiveling action also provides for the adjustment of the seat vertically. This mechanism, in the preferred form illustrated in Figs. 7-9, comprises an externally screw threaded member 80 having an integral peripheral flange 81 at its upper end. The flange provides a bearing of substantial area and may be attached to the bottom plate 72 of the seat frame as by wood screws 82. The member 30 80 is adapted to engage in a companion internally threaded member in the form of a sleeve or bushing 83 fitted in an aperture 84 in the top member 70 of the base. The bushing is formed with a peripheral flange 85 adapted to rest on the top member and it may be secured in place thereon by means of wood screws 86.

35 Preferably the threaded member and the cooperating bushing are of relatively large diameter to provide firm support for the seat. The length of the threaded member is determined by the range of vertical adjustment required. Thus when a substantial portion of the adjustment is obtained through the medium of the tongue and groove mounting of the seat assembly on the seat frame, the threaded member may be relatively short, thus reducing the amount of metal required in the construction of the chair. On the other hand, the provision of a single groove for mounting the seat assembly will necessitate a somewhat longer threaded member to obtain the necessary range of adjustment.

40 In order to prevent undesired raising of the seat and possible disengagement of the threaded member 80 from its socket by inadvertent rotation of the seat frame and additionally to maintain the seat in predetermined relation to the base, I provide means for limiting the range of rotation of the seat frame with respect to the base. This means, of course, is constructed so as to be readily releasable and thus permit of adjustment when required. As herein shown, the means provided for this purpose comprises a headed bolt 87 anchored in the top member 70 of the base and arranged to project through an 45 arcuate slot 88 in the bottom plate 72 of the seat

frame. It will be appreciated that slot 88 may be formed in the top member 70 of the base, if desired, in which case the bolt 87 will be anchored to the bottom plate 72 of the seat frame. With this arrangement, limited swiveling of the seat is permitted yet the seat is always held in a forwardly facing position so that the supporting legs do not interfere with the proper use of the chair. Moreover, by simply removing the bolt 87, the seat frame may be turned for raising and lowering as required. Access to the bolt for removal is readily obtained by sliding the seat assembly to the forward position or, if desired, the seat assembly may be removed from the chair by simply sliding it out of the supporting grooves as previously explained.

The second modified form of chair shown in Figs. 10, 11 and 12 differs from the previously described swivel chair in that vertical adjustment is obtained solely through the use of combined swiveling and height adjusting mechanism, while depth adjustment is obtained in simple and efficient manner now to be described. Referring to Figs. 10-12, the seat frame 71' of the chair is similar to the seat frame 71 except that side panels 73' instead of being horizontally grooved are formed with a series of horizontally spaced vertical notches 90 in their inner faces. Seat assembly 16' is similar to the seat assembly 16 except that the supporting members 35' are formed with outwardly facing vertically disposed ribs 91 instead of horizontal tongues. The ribs 91 are dimensioned to fit into the notches 90 and thus locate the seat assembly with respect to the seat frame, the seat assembly resting on the bottom plate 72 of the frame. It will be evident that the seat assembly may be set in any one of a plurality of horizontally adjusted positions by simply lifting the tongues 91 from the notches 90 and reinserting them in a different selected set of the notches.

The swiveling and adjusting mechanism of this chair may be exactly like that previously described except that in this case it may be desirable to employ a somewhat longer threaded member 80' to provide the range of adjustment required. Undesired rotation of the seat frame is prevented by limiting means similar to that described hereinbefore.

It will be apparent from the foregoing that the invention provides a posture chair of novel and improved construction. Although constructed substantially entirely of wood, the chair embodies all the advantages of adjustability usually found only in all-metal chairs. The metal required for the construction of the improved chair has been reduced to a negligible amount which is an extremely important consideration when conditions necessitate restricted use of metals for products of the class under consideration.

Adjustment of the seat for both height and depth is readily attained through the medium of the novel seat supporting and guiding arrangement provided by the invention. Moreover the seat may be readily removed from the chair for recovering or other purposes. Removable covers of the draw-cord type are employed and these covers are securely held against displacement when the chair is in use.

The chair also comprises a novel swiveling back rest which is readily adjustable both for height and for angular position independently of the seat adjustments. By reason of the novel construction employed, the parts are securely held against warping or any other changes from the

initial form provided. The novel form of the back rest also facilitates removal and replacement of the cover.

The invention further provides a novel swiveling and height adjusting mechanism particularly suitable for use with chairs of wooden construction. This swiveling mechanism requires relatively little metal in its construction, the advantage of which will be readily appreciated. Undesired changes in the seat height and disengagement of coacting parts is prevented by limiting the swiveling movement of the seat in the normal use of the chair, while provision is made for temporarily removing these limitations when it is necessary to adjust the seat. Adjustment for depth of the seat, that is, adjustment of the seat from front to rear with respect to the base of the chair, is obtained in a simple and effective manner without the use of complicated mechanisms or metal fittings.

In general, chairs constructed in accordance with the present invention are strong and sturdy and well adapted to perform their intended function. Moreover, the chairs are attractive in appearance and well suited to use in modern offices, schools and the like requiring posture chairs of this general character.

I claim as my invention:

In a chair structure, in combination, a base, a seat member, means supporting said seat member on said base for vertical adjustment and for front to rear adjustment in a horizontal plane, said supporting means comprising a pair of elongated supporting members rigid with and depending from the seat member adjacent opposite sides of the same, outwardly facing elongated guide elements extending along the lower edges of said supporting members, said base including a pair of upright side panels spaced apart to receive said supporting members with a relatively snug fit, each of said side panels having a series of horizontally disposed grooves adapted to slidably receive said guide elements and spaced apart vertically to provide a plurality of adjusted positions for said seat member, and front and back end panels extending between the front and rear ends of said side panels to close the ends of said grooves and to define the forward and rearward adjusted positions of said seat member, one of said end panels being removable to permit transfer of said guide elements from one set of grooves to another for vertical adjustment of the seat member.

NATHANIEL T. SHEPHERD.
